LIQUID APPLICATOR FOR PACKAGING MACHINES AND THE LIKE

Robert Rutherford, Springfield, Pa., assignor to Sun Oil Company, Philadelphia, Pa., a corporation of New Jersey

Application May 16, 1951, Serial No. 226,566

1 Claim. (Cl. 15—127)

This invention relates in general to an apparatus for applying a liquid coating to a surface, and more specifically to a device for applying a controlled quantity of liquid as a coating on a surface wherein there is relative movement between the apparatus and surface.

The application of liquids as finishes, lubricators, seals and like purposes has introduced applicators of varied designs. Generally, the only requirement to be met is that of smearing a surface with a liquid in insufficient quantity to drip or run. Where moving surfaces are concerned, excess quantities are usually removed by a wiper coupled with the applicator. This combination of devices interferes with production operations and increases the cost of the treated product. In continuously operating production lines, such as are represented by extruders where the final step is a completed package, it is necessary to rigidly control the application of the liquid without intervening apparatus. It is an object of the invention to provide an efficient device for directly applying a regulated evenly distributed coating of liquid to a surface wherein there is relative movement between the apparatus and the surface.

The invention consists of a reservoir for holding a quantity of the liquid to be applied on the moving surface. Sealed in the lower part of the reservoir, a porous body is subjected directly to the liquid and transmits it throughout the entire mass equally, and at controlled flow. The liquid quantity passing through the porous member is received by an absorbent pad which further distributes it, but does not alter the flow control of the porous body. The absorbent pad fills the remaining volume of the reservoir housing and extends downwardly to thrust against a replaceable fabric cover which is the surface for contacting the moving body.

In order that a better understanding of the invention may be had, reference is made to the following detailed description and the accompanying drawings in which:

Figure 1 is a plan view of the device on the applicator side.

Figure 2 is a side elevational view of the applicator.

Figure 3 is an end elevational view of the applicator.

Figure 4 is a sectional view along lines 4—4 of Figure 2.

The conditions for which the disclosed apparatus is designed are generally associated with production line packaging. The operation is continuous and the coating of the liquid supplied by the device is required to be positive yet controlled in quantity. These requirements are found in moistening adhesive bindings for sealing purposes, in coating contact surfaces of packaged items which tend to stick together in storage or shipment such as cakes of wax, and for other similar conditions.

According to the present invention, advantage is taken of the control and distribution of coating material maintained in form of flowing liquid to pass easily and accurately through a porous member for even flow and distribution. Abutting the porous member, a body of

2

absorbent material receives the liquid for application to the receiving surface through a replaceable fabric cover. The porous and absorbent members afford a liquid control which is novel and particularly useful under the noted application. Valves and other controls which intermittently flood and dam the movement of the liquid to the absorbent member are eliminated.

Referring now to the drawings, in which the same elements are indicated by the same numeral, the covered reservoir housing 10 is adapted to receive and store a liquid volume 12 in the upper section. The liquid is admitted to the reservoir through the tapped aperture 13 in which a pipe connection will fit. A supply of liquid is furnished under a selected pressure head from a source not shown as the supply method and apparatus do not form a part of this application. It is only necessary that the pressure head be known and constant as will be fully understood later in the specification. As indicated by the dotted lines in Figure 2 and the sectional Figure 4, the section of the housing 10 devoted to the liquid volume, is sufficiently large relative to the porous body 14 to permit even and complete distribution of the liquid at constant pressure to the absorbent pad 16. This distributed and controlled flow of liquid is transmitted to the absorbent pad which projects downwardly between the clamping bars 18 and is smoothly supported by the fabric cover 20. The projecting segment of the absorbent pad 16 should be equal in width to that of the moving surface to be coated and not depend upon the cover 20 to do any part of the liquid distribution. No brackets or other supports are shown to hold the apparatus in contact position with the moving surface, as they are well known and do not form a part of the invention.

Repeated or sustained use of the applicator will wear or clog the pores of the fabric 20. It is, therefore, designed to be easily replaced with the same or other material to assist the operation. The groove 22 in the side rails 24 of the reservoir body are fashioned to receive the extended fabric as shown in Figures 3 and 4. In Figures 1 and 2, the cover 20 is shown only in small sections to indicate position and coverage; otherwise, it is deleted from these figures for clarity of the remaining detail. Resilient fasteners, such as the springs 26 are mounted on each end of the reservoir housing to stretch the wires 28 in the grooves 22 to hold the fabric closely against the bottom of the absorbent pad.

In the preferred embodiment, the device is used under conditions of atmospheric pressure aided only by the static head of the liquid filling the reservoir and the supply source. It is evident to those versed in the art that additional pressure can be applied through the tapped aperture 13, or the source, and the device used in the inverted or other position to coat surfaces as desired. The use for which this applicator is designed, namely coating the upper surface of a moving body in a production line, such as a moistener for seals, or applying an anti-adhesive liquid to commercial items prior to packaging, requires the device to be used as indicated in Figure 2 of the drawing.

Under such conditions, particularly in the application of an anti-adhesive to prevent sticking, as in packaging wax cakes, excessive amounts of the liquid may adversely affect the item or damage the container. It is required in such cases to apply predetermined quantities of the liquid as a coating on the surface of the wax cakes to be packaged which will be in contact with a like surface of another cake. A liquid for this purpose is described and claimed in an application Serial Number 190,057, filed October 13, 1950 now Patent No. 2,643,973.

The porous member of the preferred embodiment is built up by assembling a plurality of comparatively thin members of uniform porosity. Any material having this

qualification may be used, such as pressed fibre, wood, porous metal, etc. However, the available porous metal sheets used commercially as lubricant absorbing bearings, are especially well adapted to this purpose. Other porous metal sheets, such as those manufactured by the pressing of dry metal filings and other processes, are especially well adapted to the formation of this member. The number of layers of the selected material can be increased or decreased depending on the viscosity of the liquid and the operating conditions. As indicated, a uniform flow of liquid to supply the exact amount of coating to a surface moving beneath and in contact with the fabric cover over the area of the absorbent pad, is the result.

An application of the device usable as an example is found in coating wax cakes with a non-sticking preparation preliminary to packaging in cardboard cartons for storage and shipment. An oil for this purpose is disclosed in the application of reference and is noted as covering a wide range of viscosities. Such a liquid is supplied to the reservoir space of the housing 10 in direct contact with the porous member 14. A simple float control arrangement maintains the reservoir full of the liquid under constant pressure at all times. The thickness or number of layers of material in the porous member 14 is determined to transmit the proper flow of liquid to coat the wax cakes. As the most desirable location of the device in this example is adjacent the extruder nozzle in order to coat the moving surface before the wax cake is distorted by cooling, it is fastened to existing structure of the extruder by simple brackets. The dimensions of the absorbent pad 16, projecting downward from the housing 10 are such as to give a width equal to the wax cake and a length along the wax-cake ribbon to form an area capable of supplying sufficient liquid to the continuously moving surface.

In this example, it has been determined to coat the wax cake surface (12" x 18") with 1 cc. of anti-adhesive liquid. By test, it has been determined that this quantity will prevent objectionable adhesion and will not wet the containers with consequent weakening in storage or transit. This flow, for the particular liquid used and under the conditions of operation, is obtained by a definite number of porous metal plates, each of a specified thickness. Under one condition of operation, this number was found to be one of a commercially available plate .062 inch thick. The invention is not restricted to this particular material, but will also use wood, fibre, and other materials capable of manufacture into uniform porous sections as indicated.

The feed of the liquid through the porous member to the absorbent member having been established, the fabric cover 20 is the contacting surface with which the wax cake surface rubs as it passes beneath the applicator. The absorbent pad used was of felt which was covered by a piece of muslin. The wax cakes, of our example,

remove a quantity of the liquid from the absorbent pad commensurate with the feed of the liquid through the porous member. As the operation is continuous and uniform the proper amount of liquid is received on the wax cake surface. If wax particles and other foreign material should eventually clog the pores of the fabric cover it may be necessary for this reason to renew it. However, the effectiveness of the fabric cover is very seldom affected by clogging with foreign material, but is normally worn out in contact and replacement is needed only at long intervals. It is used primarily, in our example, to keep the wax cakes free of hairs from the felt pad, retain the operating dimensions of the felt absorber, and as noted to give an interchangeable wearing surface protecting the pad from undue wear and tear. Provision has been made for easily renewing this part of the device.

From the above description and example, it is apparent that an apparatus is provided which will coat a moving surface uniformly with a liquid. The arrangement of the liquid flow control members between the liquid supply and the moving surface is such as to evenly distribute the required quantity of liquid uninterruptedly for long periods of time as required by production line methods. Furthermore, the apparatus provides an easily assembled, repair-free applicator requiring no maintenance, which will function uniformly in the desired manner.

What is claimed is:

30 An applicator for controlled continuous application of liquid to surfaces moving relatively thereto, the same comprising an elongated open-bottomed housing the top of which is provided with a constantly open orifice for continuous inflow of liquid, a pad and above it a pervious liquid distributor closing the bottom of the housing, 35 clamping bars extending along the bottoms of the side walls of the housing and confining said pad against said distributor and said distributor against shoulders formed on said side walls, the space between the distributor and the top of the housing forming a reservoir adapted to be 40 completely and continuously filled by the continuous inflowing liquid; the pad, secured to the housing as specified, projecting below the housing, and a fabric sheet 45 for contact with said moving surface extending under the pad and under the clamping bars with its longitudinal edges secured to the opposite longitudinal walls of the housing.
